(57) **CLAIM**

The ornamental design for an audio headset, as shown and described.

DESCRIPTION

FIG. 1 is a front elevational view of an audio headset showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a front, top and left side perspective view thereof;

FIG. 8 is a rear, bottom and right side perspective view thereof;

FIG. 9 is a rear, top and right side perspective view thereof;

FIG. 10 is a front, top and left side perspective view showing the audio headset in a first use state;

FIG. 11 is a rear, bottom and right side perspective view showing the audio headset in a second use state; and,

FIG. 12 is an enlarged view of portion 12 in FIG. 7.

The broken lines in the drawings illustrate portions of the audio headset and environmental subject matters that form no part of the claimed design.

The audio headset is shown with a symbolic break in its length. The appearance of any portion of the article between the break lines forms no part of the claimed design.

The dash dot broken lines encircling a portion of the audio headset in FIG. 7 and illustrated in the enlarged view of FIG. 12 form no part of the claimed design.
